(57) **CLAIM**

(51) **LOC (8) Cl.** **08-08**

The ornamental design for an apparatus for clamping a workpiece, as shown and described.

(52) **U.S. Cl.** **D8/397**

DESCRIPTION

(58) **Field of Classification Search** D8/382,

D8/387, 397, 398, 399; 411/81, 98, 103, 411/106, 145, 146, 172, 179, 197, 204, 248,

411/337, 338, 368, 371.2, 372.5, 418, 427, 411/429, 430, 431, 432, 436, 437, 500, 511, 411/512, 514, 531, 532, 533, 535, 536, 537, 411/538, 542, 544, 918, 526, 928; 70/229; 301/35.623, 111.01; 267/159; 269/32, 137

See application file for complete search history.

FIG. 1 is a front elevational view of an apparatus for

(56) **References Cited**

clamping a workpiece, showing my design;

U.S. PATENT DOCUMENTS

FIG. 2 is a rear elevational view thereof;

2,877,817 A * 3/1959 Rockwell 411/106
D208,429 S * 8/1967 Holliday D8/397
D262,354 S * 12/1981 Kishida D8/397
4,396,327 A * 8/1983 Menke 411/103
6,021,532 A * 2/2000 Ricks 411/535
6,308,943 B1 * 10/2001 Fischer et al. 269/32
6,609,705 B1 * 8/2003 Schindler et al. 269/32

FIG. 3 is a right side elevational view thereof, the left side elevational view being a mirror image of the side view shown;

FIG. 4 is a top plan view;

FIG. 5 is a bottom plan view;

FIG. 6 is a cross-sectional view thereof taken in the direction of the arrows along line 6—6 of FIG. 4; and,

FIG. 7 is a front elevational view thereof showing the design when used for the workpiece.

The broken line illustration of the workpiece shown in FIG. 7 and the broken line showings in each of the figure views are for illustrative purposes only and form no part of the claimed design.
